UNITED STATES PATENT OFFICE.

JOHN A. CONNOLLY, JR., OF BROOKLYN, NEW YORK.

METALLIC COLLAPSIBLE LIFE-BOAT.

1,121,481.

Specification of Letters Patent. Patented Dec. 15, 1914.

Application filed March 4, 1914. Serial No. 822,467.

To all whom it may concern:

Be it known that I, JOHN A. CONNOLLY, Jr., a citizen of the United States, residing at Brooklyn, in the county of Kings and 5 State of New York, have invented new and useful Improvements in Metallic Collapsible Life-Boats, of which the following is a specification.

This invention relates to metallic collapsible life boats and it consists in the novel 10 features hereinafter described and claimed.

An object of the invention is to provide a boat of simple and durable structure especially adapted to be used for life saving 15 purposes and with this object in view the boat comprises a hull which by its structure is rendered buoyant and having side sections movably mounted at the edges of the hull and adapted to be extended to form the 20 sides of the boat above the deck of the hull. Braces and supports of especial design are provided for holding the said side sections in extended relation and these braces and supports when not in use may be swung 25 down in compact form so that the boat when upon the deck of a vessel occupies but small space.

In the accompanying drawing:—Figure 1 is a plan view of the boat with parts 30 broken away and parts in section. Fig. 2 is a side elevation of the boat parts being shown in section and cut on the line 2—2 of Fig. 1. Fig. 3 is a transverse sectional view of the middle portion of the boat cut on the 35 line 3—3 of Fig. 1. Fig. 4 is a side elevation of the intermediate portions of the side sections of the boat showing one of the means employed for supporting the same in extended position. Fig. 5 is a transverse 40 sectional view cut on the line 5—5 of Fig. 4. Fig. 6 is a horizontal detailed sectional view cut on the line 6—6 of Fig. 5. Fig. 7 is a perspective view of a portion of one of the side sections. Fig. 8 is a side elevation 45 of another support used upon the boat for holding the side sections in extended position with relation to each other.

The boat includes a hull indicated in general at 1 and which is preferably formed 50 from sheet metal. The plates of which the hull is composed may be secured in any suitable or appropriate manner. Center and middle timbers 2 extend longitudinally of the hull and constitute what is generally known in the art, as back-bones. Frames 3 extend transversely across the hull 1 and the end portions of the said frames are con-

nected together by means of clamps and stringers 4 which extend the full length of the boat and which are curved to the general line of curvature of the side portions of the hull 1. A metal deck 5 is positioned upon the upper edges of the back-bones 2 and the frames 3 and covered with wooden decking between the side tanks. Side seats 6 extending the full length of the side tanks 7 are located above the edges of the deck 5, these water-tight tanks 7 being located under the said side seats 6, and each water-tight compartment in said tank is provided 10 with a nipple indicated at 8 in Fig. 3. The said tanks are divided into water-tight compartments which are capable of supporting the entire boat if the hull proper is rendered useless. These water-tight compartments if 15 desired are also adapted to be utilized for the storage of fuel, food or other necessities of a life saving nature. The spaces between the back-bones 2 and frames 3 are divided by partitions 9 into compartments 20 80 10 and these compartments are to be airtight. The said compartments will further contain cork (not shown) and consequently should any one of the compartments be 85 punctured when the boat is in use, so that the air may escape from the said compartments, the buoyancy of the cork contained therein will be sufficient to maintain the buoyant nature of the hull comprised of the compartments in which the cork is located. 90 The side seats 6 are connected together at intervals along the length of the boat by cross seats 11. A stop or bead 12 extends around the outer side of the edge portion of the hull 1, and is grooved as indicated at 12' 95 for the purpose of receiving the edge of the lowermost section 13 when the boat is collapsed.

Telescopic side sections 13, 14 and 15 are mounted at the edge of the hull 1 and these 100 sections are preferably formed from plates of sheet metal. Each of the said sections is provided at its lower edge with an angularly disposed flange 16 and the flanges of the outermost sections bear against the outer surfaces of the next adjacent sections. Groove plates 17 are mounted on the under sides of each of the sections 13—14 and 15 and are spaced at suitable intervals apart. The said grooved plates are adapted to receive studs 18 located on the outer top side of the next lower adjacent plate. Also studs 110 similar to the studs 18 and indicated at 18' in Fig. 5 are mounted at the top side edges

of the hull 1 and are received in the grooves of the groove plates 17 affixed on the inner side of section 13. A gunwale 19 is supported at the upper edge of the section 15 and the grooved bead 12 is located in the path of movement of the lower ends of the sections 13, 14 and 15.

When the parts of the boat are in set up or extended position as shown in Figs. 1 10 and 3 of the drawings, metal struts or cross braces 20 are interposed between the gunwales 19 which are on opposite sides of the boat and the intermediate portions of the said struts or cross braces 20 are braced 15 with relation to the deck 5 by means of braces 21 which are pivotally connected with the said struts or cross braces and which are provided at their lower ends with balls 22 adapted to enter socket members 23 20 fixed to the deck 5 of the boat.

The cross seats 11 of the boat which are located preferably above the side seats 6, are provided with openings 24 and the said openings are provided with pins 25. Braces 25 26 are pivotally connected with the gunwales 19 and are provided with flexible spaced ends 27 adapted to enter the openings 24. The ends 27 are provided with openings 30 adapted to receive the pins 25 whereby the braces 26 are held in the inclined positions as shown in Fig. 3 of the drawing, when the parts of the boat are set up or extended. The said braces 26 when in the position described serve as means for bracing the intermediate portions of the gunwales 19 with relation to the seats 11 and 6. When the gunwales 19 are lowered the ends 27 of the braces 26 are moved toward each other whereby the ends of the said braces are disconnected from the pins 25 and the braces 40 may be swung into approximately horizontal position and may extend along the seats 11 when the gunwales 19 are lowered.

Other braces 28 are pivotally connected 45 with the side seats 6 and the said braces are provided at their free ends with hook extremities 29 adapted to be engaged in socket members 30 mounted at the under side of the gunwales 19. The detailed structure of 50 the braces 26 and their coöperating parts are best illustrated in Fig. 8 of the drawing. Studs 31 are mounted at the inner sides of the sections 14 and the braces 28 carry at 55 their sides sockets indicated at 32 in Fig. 8, which are adapted to receive the studs 31 when the braces 28 are disposed approximately in vertical position and consequently the side sections 13, 14 and 15 are held in proper relation with respect to each other 60 when the parts of the boat are extended or set up. The braces 28 may be positioned at desired intervals along the length of the boat and the said braces may also be posi-

tioned at the ends of the same. The boat 65 may further be provided with suitable bail- ing pumps and means for stepping a mast if desired. Presuming that parts are in the 70 positions as shown in Fig. 3 of the drawings, the braces 21 are swung so that their ends 22 are removed from the socket 23 and permits 75 the struts or cross braces 20 to collapse with sections 13, 14 and 15. The lower ends of the braces 26 are disconnected at the same 80 time from the pins 25 as are also the upper ends of the braces 28 which are swung in a 85 downward direction. The sections 13, 14 and 15 will then descend by gravity along the side edges of the hull 1 until the said 90 sections come in contact with the grooved stop bead 12, when they will assume a folded 95 position as indicated in dotted lines in Fig. 5 of the drawing. Therefore, when the parts are folded or collapsed as indicated, the boat will occupy but small space. To 100 set the parts up the operation above de- 85 scribed is reversed and consequently when the boat is launched it may contain quite a number of people and will safely ride on the surface of the water.

Having described the invention what is 90 claimed is:—

1. A boat comprising a hull, telescopic side sections located at the edges of the hull, means for holding the sections in extended positions with relation to each other and 95 bracing means adapted to be interposed between the sections at the opposite sides of the hull.

2. A boat comprising a hull, telescopic side sections mounted at the edges of the 100 hull, stud and plate connection between the said side sections for limiting the relative movement thereof, and means for holding the sections in extended positions with relation to each other.

3. A boat comprising a hull, telescopic side sections mounted at the edges of the hull, foldable means for holding the sections in extended position with relation to each other and means for bracing the sections 110 against each other and transversely of the hull.

4. A boat comprising a hull, telescopic side sections located at the edges of the hull, a brace pivotally connected with one of the 115 side sections and having resilient ends and pins mounted above the hull and adapted to be engaged by the end portions of the said brace for holding the sections in extended position with relation to each other.

In testimony whereof I affix my signature in presence of two witnesses.

JOHN A. CONNOLLY, JR.
